CLAIM

(22) Filed: **Jun. 1, 2006**

The ornamental design for, a rear portion of a motorcycle, as shown and described.

(30) **Foreign Application Priority Data**

Dec. 2, 2005 (JP) 2005-035663

DESCRIPTION

(51) **LOC (8) Cl.** 12-11

FIG. 1 is a front elevation view of a rear portion of a motorcycle, showing our new design;

(52) **U.S. Cl.** D12/110

FIG. 2 is a rear elevation view thereof;

(58) **Field of Classification Search** D12/110,
D12/126, 181, 186; 180/219; D26/28-36;
362/473, 497, 506; 280/152.1-152.3, 288.4,
280/160, 160.1, 852, 854; 293/105

FIG. 3 is a top plan view thereof;

See application file for complete search history.

FIG. 4 is a right side elevation view thereof;

(56) **References Cited**

FIG. 5 is a left side elevation view thereof;

U.S. PATENT DOCUMENTS

FIG. 6 is a perspective view thereof;

D481,980 S * 11/2003 Song D12/186
6,695,330 B2 * 2/2004 Hata 280/152.3

7,114,836 B2 * 10/2006 Sheu et al. 362/473

FIG. 7 is an enlarged front elevation view thereof;

FOREIGN PATENT DOCUMENTS

FIG. 8 is an enlarged right side elevation view thereof; and,

JP 925625 S 5/1995

FIG. 9 is an enlarged perspective view thereof.

The pattern of longer and shorter broken lines define the

boundaries of the claimed rear portion of a motorcycle and

form no part of the claimed design, while the other broken

lines show the environment of the rear portion of a motor-

cycle and form no part of the claimed design.
